(57) **CLAIM**

The ornamental design for a lock for panel mount, as shown and described.

DESCRIPTION

FIG. 1 is a front, top and right side perspective view of a lock for panel mount, showing the new design;
FIG. 2 is a rear, top and left side perspective view of the lock for panel mount in FIG. 1;
FIG. 3 is a front elevation view thereof;
FIG. 4 is a top plan view thereof;
FIG. 5 is a rear elevation view thereof;
FIG. 6 is a bottom plan view thereof;
FIG. 7 is a left side elevation view thereof;
FIG. 8 is a right side elevation view thereof;
FIG. 9 is a second front, top and right side perspective view of the lock for panel mount in FIG. 1;
FIG. 10 is a second rear, top and left side perspective view of the lock for panel mount in FIG. 1;
FIG. 11 is a front, top and right side exploded perspective view of a lock for panel mount, showing the new design;
FIG. 12 is a rear, top and left side exploded perspective view of the lock for panel mount in FIG. 11;
FIG. 13 is a front elevation view thereof;
FIG. 14 is a top plan view thereof;
FIG. 15 is a rear elevation view thereof;
FIG. 16 is a bottom plan view thereof;
FIG. 17 is a left side elevation view thereof;
FIG. 18 is a right side elevation view thereof;
FIG. 19 is a second front, top and right side exploded perspective view of the lock for panel mount in FIG. 11; and,
FIG. 20 is a second rear, top and left side exploded perspective view of the lock for panel mount in FIG. 11.
